UNITED STATES PATENT OFFICE

2,298,796

METHOD AND APPARATUS FOR PICTURE TRANSMISSION

Ray D. Kell, Haddonfield, N. J., assignor to Radio Corporation of America, a corporation of Delaware

Application August 31, 1939, Serial No. 292,925

7 Claims. (Cl. 178—7.2)

My invention relates to the transmission of pictures and has for its object to provide an improved method of and means for so transmitting pictures from motion picture film or the like that the picture may be reproduced at the receiver with the proper background or average overall illumination. According to one aspect of the invention, it provides a system wherein the direct current component of the video signal may be reinserted at any point in the system in cases where this component has been lost as a result of passing the signal through alternating current amplifiers, transformers, or the like. According to another aspect of the invention, it makes possible the transmission of video signals including the direct current component through an alternating current amplifier or the like without any change in the location of their alternating current axis.

In applying a preferred embodiment of my invention to a television transmitter, there is employed a cathode ray picture transmitter tube of the type recently described by Iams and Rose. The main feature of this tube is that the electron beam velocity is so low at the point of impact at the mosaic that the secondary emission ratio is less than unity. I have observed that when motion picture film is transmitted by projecting the picture frames upon the cathode ray tube mosaic during the return line periods only and then scanning the mosaic after the light has been cut off, the signal level representative of black in the picture corresponds exactly with the position of the A. C. axis of the signal. The reason for this is that the signal produced during a return line period (during which period a light image is projected upon the mosaic) is a result of electrons leaving the whole mosaic in proportion to the light and shade of the picture, while that produced during the useful scanning period is a result of the same number of electrons being replaced on the surface of the mosaic. Stated in another way, the integrated signal amplitude with respect to time during the image projection period is exactly equal to the integrated signal amplitude with respect to time during the useful signal period.

Thus, it will be apparent that a signal of the above-described character may be transmitted through a system including alternating current amplifiers without any shift in the position of the A. C. axis. In other words, the D. C. component of the signal would not be lost.

However, because of the large amplitude of the signal pulse produced during the return line

period, it is preferred to clip off the greater part of it in an early amplifier stage and to utilize the resulting signal later for reinserting the direct current component.

The invention will be better understood from the following description taken in connection with the accompanying drawings in which

Figure 1 is a diagram showing one embodiment of the invention as applied to a television transmitter,

Figure 2 is a circuit diagram of a portion of the transmitter shown in Figure 1,

Figures 3, 4, 5 and 6 are curves which are referred to in explaining the invention,

Figure 7 is a diagram showing the clipping action which occurs in the circuit shown in Figure 2,

Figure 8 is a curve illustrating the character of the video signal which is transmitted to the receiver,

Figure 9 is a circuit diagram of a portion of a television transmitter illustrating another embodiment of my invention, and

Figures 10 and 11 are diagrams which are referred to in explaining the operation of the circuit of Figure 9.

Referring to Fig. 1, the cathode ray picture transmitting or pickup tube is shown at 1. This tube, which is of the type wherein the electron beam approaches zero velocity at the mosaic screen, is described specifically in Patent No. 2,213,175, issued Aug. 27, 1940, in the names of Harley A. Iams and Albert Rose, and assigned to the Radio Corporation of America. It is also described as to the principle of operation in Patent No. 2,213,174, issued Aug. 27, 1940, in the name of Albert Rose, and assigned to the Radio Corporation of America.

The pickup tube 1 comprises a highly evacuated envelope having therein an electron gun which consists of an indirectly heated cathode 2, a control electrode 3 and accelerating electrodes 4 and 6. Suitable biasing and accelerating voltages are provided by the batteries 7 and 8.

By means of a focusing coil 9, the electron beam leaving the electron gun is focused to a small spot on a mosaic screen 11. The screen 11 is of the well-known type commonly employed in iconoscopes with the exception that it is made translucent whereby the image of a frame of the motion picture film 12 to be transmitted may be projected on the photoelectric elements of the screen from the back side by means of a suitable optical system indicated at 13.

The electron beam is caused to scan the screen

11 by means of deflecting plates 14 and deflecting coils 16, the plates 14 preferably being curved as described in the above-mentioned Iams and Rose patent for the purpose of eliminating distortion in scanning.

12 An electrode 17 having a slot 18 therein is provided for electrostatic shielding purposes. A centrally apertured electron-collecting electrode 19 is provided to which the electrons of the beam 10 not reaching the mosaic screen 11 are directed and collected.

13 As explained in the above-mentioned Rose patent, the electrons of the electron beam are directed upon the mosaic screen 11 with a very low velocity, that is, a velocity approaching zero velocity at the point of impact therewith. The reason for employing this low velocity is that the electrons of the beam should approach the point of impact on the mosaic with a velocity such that the ratio of secondary electrons to primary electrons is less than unity.

14 In operation, elemental areas of the mosaic electrode acquire electrostatic potentials proportional to the intensity of light incident thereon. Particles of the mosaic which are more highly illuminated acquire the most positive electrostatic charge with respect to the unilluminated particles. The positive charges representing an electrostatic image of a picture to be transmitted are neutralized by the scanning beam electrons. When the electrons of the scanning beam are directed toward those particles of the target which are negative with respect to the cathode, they cannot reach those particles because of their low velocity. These electrons, since they are prevented from impinging on the target are returned to an electron collecting electrode adjacent the electron gun. The scanning means which causes the electron beam to scan the mosaic electrode or target are so chosen as to prevent those electrons of the beam which do not reach the target from returning to the electron gun but rather causes them to be redirected along paths other than those followed by those electrons in traversing the distance between the electron gun and the target.

15 A tube of the above type has a linear characteristic between light input and signal output. It is so adjusted that when the mosaic screen 11 is dark all of the electrons of the electron beam are repelled and returned to the collector electrode 19. Any light on the screen 11 causes some of the electrons of the beam to reach the screen for neutralizing the positive charges which the light has caused the photoelectric capacity elements to assume. This neutralizing current is the picture current. Preferably, it is taken off the back or signal plate of the screen 11 and supplied to a picture amplifier 45 through an output resistor 30.

16 Referring now more specifically to the circuit associated with the pickup tube, there is provided a suitable synchronizing signal and blanking impulse generator indicated at 26. This generator preferably supplies synchronizing and blanking signals similar to those described in Bedford British Patent 448,065. It may comprise rotatable discs having apertures therein corresponding to the impulses desired as described in the said British patent, or it may comprise vacuum tube oscillators and shaping circuits as described in Smith Patent No. 2,132,655.

17 Synchronizing or driving impulses occurring at the vertical deflecting frequency are supplied over a conductor 27 to a suitable vertical deflect-

18 ing circuit 28 which forces the desired saw-tooth current through the deflecting coils 16.

19 Likewise, synchronizing impulses occurring at the horizontal deflecting frequency are supplied over a conductor 29 to a suitable horizontal deflecting circuit 31 which impresses a saw-tooth deflecting voltage across the deflecting plates 14.

20 The basic method of transmitting the motion picture film is that described in my Patent No. 2,166,214, issued July 18, 1939. Preferably, the system employs the so-called 2-3 intermittent mechanism described in Bedford Patent No. 2,082,093, which makes possible the transmission of standard 24-frame-per-second film at a scanning rate of 60 frames per second.

21 The film projector and associated apparatus comprises a film gate 32 through which the motion picture film 12 is drawn by means of an intermittent mechanism 33, preferably of the type described in Bedford Patent No. 2,082,093. This mechanism is driven by a synchronous motor 34 operated from the 60-cycle power line. The motor also drives a shutter disc 36 having an opening therein through which an image of a picture frame may be projected upon the cathode ray tube mosaic 11 during the return line period. In the specific example illustrated, the motor 34 operates at 3600 R. P. M., and the shutter disc has only one shutter opening whereby the shutter opens 60 times per second.

22 Obviously, the electron beam of the cathode ray tube 1 must be deflected in the proper time relation to the projector and shutter operation. This time relation is insured by the use of a control circuit 37 which holds the impulse generator 26 in a fixed time relation to the 60-cycle power supply. Such a control circuit is described in Bedford Patent No. 2,137,010.

23 Preferably, vertical and horizontal blanking impulses are supplied from the generator 26 through an amplifier 35 and a coupling condenser 40 to the control electrode 3 of the tube 1, these impulses having the proper amplitude, polarity and timing to block the electron beam during 40 both the vertical return line time and during the horizontal return line time.

24 The video signal appearing across the output resistor 30 is of the character shown in Fig. 3 where the signal produced by the picture frame being flashed or projected upon the mosaic is indicated at x, while the picture signal produced as the electron beam scans the mosaic is indicated at y. The horizontal blanking pulses cause the output signal to go to black periodically as indicated at z. It may be noted that, in order to simplify the drawing, only a small number of horizontal pulses z have been indicated. The area of the signal x above the A. C. axis is always the same as that of the signal y below the axis. 50 This is because, in the cathode ray tube used in this system, the electron beam during the scanning period merely replaces the electrons that were released from the mosaic when the picture was projected upon it.

60 65 Thus, if the scene becomes darker, the amplitude of both signal portions x and y decreases. The result is that the A. C. axis is always at the level representing "black" in the picture.

70 75 This is further illustrated in Figs. 4, 5 and 6. If the mosaic screen is dark, there is no signal, this condition being illustrated in Fig. 4. If the screen is uniformly illuminated to an intensity representing gray, the signal is as represented in Fig. 5. If the illumination is increased to the maximum illumination representing white, the

signal is as shown in Fig. 6. It will be seen that the A. C. axis has not shifted, but has remained at the level representing "black" in the picture.

From the foregoing, it will be evident that the cathode ray tube output may be transmitted to the cathode ray receiver tube through A. C. amplifiers without any loss of the direct current component of the picture. This procedure, however, has several disadvantages, one being that the amplitude of the signal produced by the light flash on the mosaic is larger (about ten times that of the picture signal, for example) whereby amplifiers are quickly overloaded, and another being that there is no way of transmitting vertical synchronizing signals of the desired characteristics.

Accordingly, it is preferred to clip off either all or a substantial portion of the impulse portion x of the video signal at a suitable point either in the preamplifier 45 or in the video amplifier 50. For example, as illustrated in Fig. 2, an early stage 31 of the video amplifier may be given a sufficient negative bias to clip off the signal portions x at the black level. This clipping action is shown in Fig. 7 where the characteristic of the tube is shown at 39. The video signal having the character illustrated in Fig. 3 is applied to the clipping tube with the pulses x in the negative direction. The pulses in the resulting signal appearing in the plate circuit of the clipping tube have a fixed amplitude at the "black" level and a varying height with respect to the alternating current axis. As will be described later, it may be preferred to first clip off the pulses x above the black level.

The video signal, after being clipped at "black" as described above, may be amplified and, after blanking and synchronizing pulses have been added thereto in the usual way to produce a signal such as shown in Fig. 8, transmitted to a receiver. The D. C. component may be reinserted at any desired point or points in the system. Preferably, direct current transmission is employed for more efficient operation in which case the direct current is reinserted at or close to the modulation stage of the transmitter. In this case, as well as where A. C. transmission is employed, the D. C. component is reinserted in the receiver at the cathode-ray tube to provide automatic background control, since the video amplifiers in the receiver are usually of the A. C. type for best operation.

Merely by way of example, there is shown in Fig. 2 a D. C. reinserting stage for D. C. transmission. This particular stage comprises an amplifier tube 41 to which the video signals are fed through a suitable number of amplifiers which have been omitted from the drawings as indicated by the broken line and through a grid condenser 42, the signals being applied to the grid of the tube 41 with the synchronizing pulses of positive polarity. The grid leak resistor 43 has such resistance with respect to the capacity of the grid condenser 42 that, due to the synchronizing impulses driving the grid positive periodically, there is produced a grid leak biasing voltage that varies in accordance with the height of the synchronizing pulses as measured from the A. C. axis. A direct current reinserting stage of this character is described in Williams British Patent No. 422,906. If preferred, the D. C. may be reinserted at the transmitter in the manner taught by Bedford application Serial No. 203,015, filed April 20, 1938, entitled "Picture transmitting apparatus," and assigned to the Radio Corporation

of America. It will be understood that the height of the synchronizing impulses rather than the height from A. C. axis to black level may be utilized for reinsertion of the D. C. component, since both the blanking impulses and the synchronizing impulses are of a fixed amplitude.

At the receiver, the D. C. may be reinserted after having been removed by the receiver video amplifier or amplifiers by means of the same type of D. C. reinserting stage as that shown in Fig. 2 or by any one of several other reinserting circuits such as the circuits shown in Holmes Patent 2,251,677, issued Aug. 5, 1941, filed February 28, 1933, entitled "Television systems," and assigned to the Radio Corporation of America. This Holmes patent claims broadly the feature of reinserting the D. C. component in accordance with the variation in height of the synchronizing impulses.

Referring more specifically to that portion of the circuit which combines the picture signals with the blanking and synchronizing impulses, it will be seen by reference to Fig. 1 that with a switch 56 closed the blanking impulses are applied to a stage of the video amplifier 50. Also, the synchronizing pulses are applied through an amplifier 57 to some stage in the video amplifier 50. For example referring to Fig. 2, the picture synchronizing and blanking signals may be added at the same point in the circuit by applying them to the amplifier tubes 58, 59 and 61, respectively, which have a common plate resistor 62.

The above-described apparatus may be operated with the switch 56 (Fig. 1) open whereby the synchronizing pulses are set directly on the picture signal at the black level. It is preferred, however, to have the pedestal or blanking portion of the final signal extend slightly beyond black as shown in Fig. 8 in order that the adjustment at the cathode-ray tube of the receiver will not be critical for obtaining good blanking, it being understood that at the receiver tube the blanking portion of the signal drives the tube to beam cut-off.

Instead of clipping the signal pulses x at the black level as described above, it is generally preferred to clip them somewhat above the black level as shown in Fig. 10. The reason this is preferred is that, unless special tubes are employed, the clipping should be done in an early amplifier stage where the signal voltage is low, in order to avoid saturating off any of an impulse x . On the other hand, vacuum tube characteristics are such that good clean clipping is difficult to obtain at low signal voltages.

It will be apparent that, when clipping is done above the black level, there must be a second clipping step in order to bring the vertical pedestals to the same level (the black level) as that of the horizontal pedestals z . Since this second clipping step is necessary, it is immaterial that the first clipping of the signal is not as complete as required in the final signal.

In Fig. 9 there is shown a video amplifier which may be substituted for the video amplifier 50 of Fig. 1 and Fig. 2. Like parts in these figures are indicated by the same reference numerals. The first clipping of the signal may be done by the tube 37 with less bias on the control grid than that indicated in Fig. 7. As a result, the pulses x are clipped beyond the black level in the black direction, as indicated in Fig. 10. It may be preferred in some cases to perform this first clipping step in one stage of the preamplifier 45,

since it should be done where the large pulses x do not saturate the amplifier. The important point is that at the first clipping stage the A. C. axis of the signal should be located at a definite level such as the black level, as distinguished from some indefinite location which would result if portions of the pulses x were saturated off before the first clipping.

After being amplified in one or more stages, the clipped signal is clipped the second time, as described above, by the tube 58 which has a variable bias applied thereto by means of a diode 66 and its associated circuit elements. The cathode of the diode 66 is connected to the control grid terminal of the tube 58, while the diode plate is connected to ground, preferably through a biasing battery 67. With this connection, negative pulses will cause a flow of diode current which charges the grid condenser 68. This charge leaks off through a grid leak resistor 69. The relative values of elements 68 and 69 are such that the discharging circuit of condenser 68 has a long time constant as compared with the frequency of occurrence of the pulses x whereby the discharge of condenser 68 applies a bias to tube 58 which follows variations in the height of the clipped pulses x as measured from the A. C. axis of the signal. This action is shown in Fig. 11. It will be seen that the diode introduces a bias voltage which holds the peaks of the pulses x at a fixed level such that they are clipped off at the desired black level.

The output of the tube 58 as shown in Fig. 11 is of the same character as that shown in Fig. 7, where the first and only clipping operation was at the black level. Therefore, it may have the blanking and synchronizing pulses added thereto in the manner previously described to produce a final signal like that shown in Fig. 8.

While no D. C. reinserting stage has been shown in Fig. 9, it will be understood that such a stage may be employed as previously described.

From the foregoing, it will be apparent that various modifications may be made in my invention without departing from the spirit and scope thereof, and I desire, therefore, that only such limitations be imposed thereon as are necessitated by the prior art and are set forth in the appended claims.

I claim as my invention:

1. A picture-transmitting system comprising in combination a cathode ray transmitter tube of the type in which there is a mosaic screen having elemental capacity elements which are electron-emissive and in which an electron beam is directed toward said screen, the electrons at the point of impact on said screen having a velocity such that the ratio of secondary electrons emitted from said screen to primary or beam electrons is less than unity, means for projecting images of a picture or scene upon said screen intermittently at a certain rate whereby periodically recurring signal pulses of a certain polarity appear in the output circuit of said tube in synchronism with said projection, means for scanning said screen with the electron beam at the end of each projection whereby picture signals of opposite polarity to said certain polarity appear in said output circuit, the resulting video signal in said output circuit having the characteristic that the alternating current axis is always at the level representing black in the picture, clipping means having a fixed bias for clipping off said signal pulses at said black level whereby pedestals are produced, means for producing periodically recur-

ring synchronizing pulses that occur simultaneously with said pedestals, and means for so adding said synchronizing pulses to said clipped video signal that they extend beyond said pedestals in the direction of black.

2. A picture-transmitting system comprising in combination a cathode ray transmitter tube of the type in which there is a mosaic screen having elemental capacity elements which are electron-emissive and in which an electron beam is directed toward said screen, the electrons at the point of impact on said screen having a velocity such that the ratio of secondary electrons to primary electrons is less than unity, means for projecting images of a picture or scene upon said screen intermittently at a certain rate whereby periodically recurring signal pulses of a certain polarity appear in the output circuit of said tube in synchronism with said projection, means for scanning said screen with the electron beam at the end of each projection whereby picture signals of opposite polarity to said certain polarity appear in said output circuit, the resulting video signal in said output circuit having the characteristic that the alternating current axis is always at the level representing black in the picture, means for clipping off said signal pulses at a fixed level beyond black, means for next clipping off said signal pulses at said black level whereby pedestals are produced, means for producing periodically recurring synchronizing pulses that occur simultaneously with said pedestals, and means for so adding said synchronizing pulses to said clipped video signal that they extend beyond said pedestals in the direction of black.

3. A picture-transmitting system comprising, in combination, a cathode ray transmitter tube of the type in which there is a mosaic screen having elemental capacity elements which are electron-emissive and in which an electron beam is directed toward said screen, the electrons at the point of impact on said screen approaching zero velocity, means comprising an intermittent mechanism and shutter for projecting images of a picture or scene upon said screen intermittently at a certain rate whereby signal pulses of a certain polarity appear in the output circuit of said tube in synchronism with said projection, means for scanning said screen with the electron beam at the end of each projection whereby picture signals of opposite polarity to said certain polarity appear in said output circuit, the resulting video signal in said output circuit having the characteristic that the alternating current axis is always at the level representing black in the picture, means for clipping off said signal pulses at said black level whereby pedestals are produced, means for producing periodically recurring synchronizing pulses that occur simultaneously with said pedestals, and means for so adding said synchronizing pulses to said clipped video signal that they extend beyond said pedestals in the direction of black.

4. A picture-transmitting system comprising in combination a cathode ray transmitter tube of the type in which there is a mosaic screen having elemental capacity elements which are electron-emissive and in which an electron beam is directed toward said screen, the electrons at the point of impact on said screen approaching zero velocity, means comprising an intermittent mechanism and shutter for projecting images of a picture or scene upon said screen intermittently at a certain rate whereby signal pulses of a cer-

tain polarity appear in the output circuit of said tube in synchronism with said projection, means for scanning said screen with the electron beam at the end of each projection whereby picture signals of opposite polarity to said certain polarity appear in said output circuit, the resulting video signal in said output circuit having the characteristic that the alternating current axis is always at the level representing black in the picture, means for clipping off said signal pulses at a fixed level beyond black before any substantial distortion of the video signal has been produced, means for next clipping off said signal pulses at said black level whereby pedestals extending to said black level are produced, means for producing periodically recurring synchronizing pulses that occur simultaneously with said pedestals, and means for so adding said synchronizing pulses to the video signal after said second clipping that they extend beyond said pedestals in the direction of black.

5. A picture-transmitting system comprising, in combination, a cathode ray transmitter tube of the type in which there is a mosaic screen having elemental capacity elements which are electron-emissive and in which an electron beam is directed toward said screen, the electrons at the point of impact on said screen approaching zero velocity, means comprising an intermittent mechanism and shutter for projecting images of a picture or scene upon said screen intermittently at a certain rate whereby signal pulses of a certain polarity appear in the output circuit of said tube in synchronism with said projection, means for scanning said screen with the electron beam at the end of each projection whereby picture signals of opposite polarity to said certain polarity appear in said output circuit, the resulting video signal in said output circuit having the characteristic that the alternating current axis is always at the level representing black in the picture, means for clipping off said signal pulses at a fixed level beyond black before any substantial distortion of the video signal has been produced by amplifier saturation or the like, means for next clipping off said signal pulses at said black level whereby pedestals extending to said black level are produced, means for also producing periodically recurring blanking and synchronizing pulses that occur simultaneously with said pedestals, and means for so adding said blanking and synchronizing pulses to the video signal after said second clipping that said blanking and synchronizing pulses extend beyond said black level in the direction of black with the synchronizing pulses set on top of said blanking pulses.

6. A picture-transmitting system comprising, in combination, a cathode ray transmitter tube of the type in which there is a mosaic screen having elemental capacity elements which are electron-emissive and in which an electron beam is directed toward said screen, the electrons at

the point of impact on said screen approaching zero velocity, means comprising an intermittent mechanism and shutter for projecting images of a picture or scene upon said screen intermittently at a certain rate whereby signal pulses of a certain polarity appear in the output circuit of said tube in synchronism with said projection, means for scanning said screen with the electron beam at the end of each projection whereby picture signals of opposite polarity to said certain polarity appear in said output circuit, the resulting video signal in said output circuit having the characteristic that the alternating current axis is always at the level representing black in the picture, means for clipping off said signal pulses at a fixed level beyond black before any substantial distortion of the video signal has been produced by amplifier saturation or the like, means for amplifying said clipped signal, means for next clipping off said signal pulses at said black level whereby pedestals extending to said black level are produced, means for producing periodically recurring blanking pulses that occur simultaneously with said pedestals, means for also producing periodically recurring synchronizing pulses that occur simultaneously with said pedestals, and means for so adding said blanking and synchronizing pulses to the video signal after said second clipping that said blanking and synchronizing pulses extend beyond said black level in the direction of black with the synchronizing pulses set on top of said blanking pulses.

7. The method of transmitting pictures in a picture-transmitting system of the type including a cathode ray transmitter tube having a mosaic screen comprising elemental capacity elements which are electron-emissive and having an electron beam directed toward said screen, the electrons of said beam at the point of impact on said screen having a velocity such that the ratio of secondary electrons to primary electrons is less than unity, said method comprising projecting images of a picture or scene upon said screen intermittently at a certain rate whereby periodically recurring signal pulses of a certain polarity appear in the output circuit of said tube in synchronism with said projection, scanning said screen with said electron beam at the end of each projection whereby picture signals of opposite polarity to said certain polarity appear in said output circuit, the resulting video signal in said output circuit having the characteristic that the alternating current axis is always at the level representing black in the picture, clipping off said signal pulses at said black level whereby pedestals are produced, producing periodically recurring synchronizing impulses that occur simultaneously with said pedestals, and so adding said synchronizing impulses to said clipped video signal that they extend beyond said pedestals in the direction of black.

RAY D. KELL.
